UNITED STATES PATENT OFFICE.

WILLIAM C. KITT, OF CINCINNATI, OHIO, ASSIGNOR TO THE KIT PAPER BOX COMPANY,
OF CINCINNATI, OHIO, A CORPORATION OF OHIO.

FOLDING BOX.

1,293,801.

Specification of Letters Patent. Patented Feb. 11, 1919.

Application filed January 28, 1918. Serial No. 214,126.

To all whom it may concern:

Be it known that I, WILLIAM C. KITT, a citizen of the United States, and a resident of Cincinnati, in the county of Hamilton and State of Ohio, have invented certain new and useful Improvements in Folding Boxes, of which the following is a specification.

My invention relates to packing or shipping boxes of the folding or collapsible kind, 10 and preferably made of paper-board, usually with a corrugated middle layer.

The object of my invention is to provide a simple and inexpensively constructed box 15 of this character provided with means whereby the box may be easily handled, and means whereby the box may be readily brought into condition for remaining in an upright position for reception of its contents, and whereby it may be readily opened 20 and closed in packing and unpacking. My improved folding box is especially suitable for the shipment of eggs, but it will be understood that I contemplate using it wherever applicable.

My invention consists in the combination of parts and in the details of construction and arrangement of parts as will herein-after be more fully described and claimed.

In the drawings:

Figure 1 is a perspective view of a folding box constructed according to my invention, the box being shown closed ready for handling and shipping;

Fig. 2 is a similar view of the box opened for packing and unpacking;

Fig. 3 is a bottom plan view of the box entirely unfolded;

Fig. 4 is a perspective view of the box in 40 partly folded condition to better illustrate the process of folding the box into upright position;

Fig. 5 is a perspective view of a box in closed condition illustrating a modification 45 of my invention;

Fig. 6 is a partial view similar to Fig. 4, but illustrating the construction of the box shown in Fig. 5;

Fig. 7 is a vertical longitudinal section on 50 a plane corresponding to the line 7—7 of Fig. 6; and

Fig. 8 is a detail perspective view of part of the clasp used in the modified construction shown in Figs. 5, 6 and 7.

As I prefer to construct my improved folding box, and as shown in Figs. 1 to 4,

inclusive, the entire box except the means for fastening its ends together and the means for fastening its top closure is made of a single piece of flat material. It will be 60 understood that this material may be any that is suitable for the purpose. For instance, it might be sheet metal or fiber or veneer; or it may be comparatively thin paste-board or card-board or other thin material of comparatively little strength. But my invention is especially adapted for being constructed of materials of considerable thickness which are not susceptible to much complicated folding, as, for instance, 65 heavy fiber or paper-board; and more especially the kind of paper-board that is made up of outer flat layers with a corrugated layer interposed. Such material is well known to be of great strength in proportion to its weight; has admirable cushioning properties; and is capable of being scored by pressure as distinguished from partial cutting, and may thereby receive simple straight bends without materially 70 lessening its strength. It will, therefore, be understood that the single sheet is of practically any suitable material, although the last named is adapted to be used according to my invention with greater facility than 75 in some other constructions heretofore known.

The single sheet 1 which would originally be plainly rectangular, has parts cut away near its four corners with slits 2 extending 80 a short distance inward longitudinally thereof short distances inward from the sides, leaving a wider and longer middle part 3 at each end flanked by narrower and shorter parts 4. Also, short distances from 85 the transverse median line of the sheet at each side are pairs of slits 5 extending transversely of the sheet very slightly farther than longitudinal lines passing through the slits 2 at the respective sides. Thus, 90 longer and wider middle parts 6 are left at each side of the sheet flanked by parts 7 continuous with the parts 4.

The longer and wider parts 3 at the ends 95 preferably have their corners cut away so that the outer ends 8 roughly conform to a curve of comparatively large radius. Slightly inward from each of these ends 8 in the middle of each part 3 are cut elongated openings 9. Farther inward, and 100 each a short distance inward from the respective slit 2 at that side, are slots 10,

each running a short distance transversely of the sheet; there being a pair of these slots 10 thus located near each end of the sheet.

- 5 The laterally outward parts 4 at the respective ends of the sheets preferably have their corners next to the slits 2 cut away, leaving rounded edges 11; and in the outer edges of these parts 4, each a short distance 10 inward from the end of the respective part 4, are elongated recesses 12 so as to leave short but wide tongues 13 adjacent to the outer corners of the respective parts 4.

The middle lateral parts 6 have punched 15 in each one of them four holes 14 lying in pairs on opposite sides of the median transverse line of the sheet, the holes of each pair being in alignment longitudinally of the sheet; one pair being located a short distance

20 transversely away from the outer edge of the respective part 6 and the other pair being located about the same distance transversely away from a line drawn longitudinally of the sheet through the inner ends of the slits

25 5. Each one of the parts 7 has two holes 15 punched in it a short distance inward from the outer edge of the respective part 7 and in alignment longitudinally of the sheet; the one hole 15 being spaced a short distance longitudinally of the sheet away from the adjacent slit 5, and the other hole being spaced about the same distance away from the line drawn transversely of the sheet through the inner ends of the slits 2.

30 35 The exact location of these holes 14 and 15, as indicated by the relation the holes 15 are to have to the holes 14, will be later described; as will also the relation of the slots 10 to the tongues 13.

40 With the sheet thus cut and provided with the openings, slots and holes, properly located as just described, and as will be further described, the sheet is folded upwardly (that is in the direction downward

45 through the drawing as shown in Fig. 3) on all of the broken lines except the lines 16 that run transversely of the parts 3 just inward from the inner edges of the slots 10 therein. Thus, the downward folding on

50 the transverse lines 17 coincident with the slits 5, and on the longitudinal lines 18 coincident with the inner ends of these slits 5 define the rectangular bottom 19 of the box. The parts 6 outside these lines 18 and

55 between the slits 5 become the inner thicknesses of the ends of the box. The downward folding on the transverse lines 20 coincident with the inner ends of the slits 2 and the downward folding on the longitudinal lines 21 coincident with these slits 2 define the rectangular sides 22; leaving parts 23

60 between the lines 20 and the lines 16 on which the folding is upward, these parts 23 together making up the top of the box; while the extreme outward parts past the

lines 16 where the folding is upward, together form the handle of the box. The remaining downward folds are on the transverse lines 24 slightly out toward the respective ends of the sheet from the inner 70 ends of the slits 2; or substantially in transverse alignment with the inner edges of the slots 10 and slightly inward from the inner ends of the recesses 12. These folds leave the parts 4 to fold over the adjacent end 75 portions of the top-forming parts 23. How these various parts come together in the folding operation is clearly shown in Fig. 4.

The holes 14 and 15 in the parts 6 and 7, respectively, as before alluded to, are so 80 located that when the parts are thus properly folded together, the holes 14 of upper pairs will register with upper holes 15, and the holes 14 of lower pairs will register with lower holes 15 in the respective parts 7, 85

which, as will be seen, come outside the parts 6 with the edges of these parts 7 abutting or at least coming close together. With the holes thus registering in the part 6 and the two parts 7 at each end of the box, suitable 90 fastening means may be readily passed through the registering holes to secure the parts 6 and 7 together. As shown in Fig. 2, this fastening means is in the form of a string 25 suitably laced through the holes 95 and tied preferably on the outside of the box as at 26. The string 25 is especially adapted for this purpose when the box is made of paper, paste-board or any kind of corrugated paper-board; and in practice 100 an ordinary shoe string serves this purpose very well and is readily inserted through the openings; the end parts of the string preferably being cut off when the tying at 26 is completed. However, it will be under- 105

stood that either with these materials or other kinds of materials where a string might not be suitable, any other suitable fastening means may be used to fasten the end parts 6 and 7 together. Also the number and location of the openings 14 and 15 may be varied; or, under certain circumstances, openings need not be provided but the fastening means of suitable character may be inserted through the parts, thus 110 making the openings as the fastening means are inserted.

As before stated, the parts 4 lap over the adjacent end portions of the top-forming parts 3; and it is the purpose of these parts 4 to complete the fastening at the top of the box. They perform this function by having their tongues 13 inserted into the slots 10; and it will be understood that the tongues 13 and slots 10 are so relatively proportioned and located that this insertion may be readily accomplished, as shown in Fig. 1.

With certain rigid materials, or where great security of fastening is not required, the insertion of these tongues 13 into these 115 120 125 130

slots 10 may be depended upon as the sole fastening means at the top. However, for most purposes and especially where paper or paper-board is the material of the sheet 1, it is preferable to have additional and auxiliary fastening means. As here shown, these consist of oblong pieces 27 which may be of any suitable material, such as metal, wood, fiber, paper-board or the like, each 5 with a longitudinal slot 28 through which passes a suitable fastener or rivet 29 into the respective part 4; thus slidably mounting the fastening piece or bolt 27 on the upper side of the part 4. This bolt 27 is so 10 mounted in this way that it is substantially aligned with the respective tongue 13 transversely of the sheet, so that when the folding of the box is completed, it may slide transversely of the box through the respective slot 10 above where the tongues 13 project into the slot and, passing out on the other side, extend over the opposite tongue 13 at that end of the box. In accordance with this purpose, the part 4 at one side is 15 provided with this bolt 27 at one end of the box, while the opposite part 4 at that end is not so provided; and at the other end the bolt 27 is preferably provided on the part 4 at the opposite side while its opposing part 20 4 is not so provided. It will be understood, however, that the relative location of these bolts at the opposite ends of the box is of minor importance; as is also the exact form of these fastening means; the essential requirement so far as the necessity of providing auxiliary fastening means extends, being 25 that some means be passed transversely through the slots 10 and engage the upper sides of both parts 4 at a respective end of 30 the box when these parts 4 are folded down on the top-forming parts 3.

In Figs. 5 to 8, inclusive, I show a modification of my invention which is chiefly concerned with this auxiliary fastening means; 45 and also concerns the fastening together of the lapped end parts of the box.

In making this modified box, the sheet 1' would be cut and folded as the sheet 1 in the first example, except that greater portions of its corner parts would be cut away 50 so as to leave no part 4; the transverse cutting lines at the corners being where the inner ends of the slits 2 are in the sheet 1, as shown in Fig. 3. Also, instead of the holes 55 14 and 15 in the parts 6 and 7, the modified corresponding parts 7' have short slots 15' of such number and so located as to coöperate with a clasp 30 fastened on the lower or outer side of the inner end part 6' (Fig. 6).

60 As here shown, this clasp 30 comprises an elongated flat body 31 having at each side a plurality of integral laterally projecting lugs 32, and having at suitable intervals in its interior suitably shaped prongs 33 65 pressed out from its material; these prongs

being adapted to pass upwardly or inwardly through the material of the part 6' and be clenched on the upper or inner side thereof, as seen in Fig. 7. Thus, the body part 31 is fixed to this inner end part 6' in a median 70 position on the outer surface thereof to extend up and down thereon with its lateral lugs 32 adapted to be bent substantially at right angles to the body 31. The series of lugs 32 at one side of the body 31 are, with the slots 15' in the outer end 7' of the box properly located therein, adapted to extend through these slots 15' in the respective parts 7' while the series of lugs 32 at the other side of the body 31 in like manner extend through such properly located slots 15' in the other part 7'. Thus extended through, they are bent inwardly across the outer sides of the parts 7' and firmly clasp 75 the parts 7' to the part 6'. 80

Each of these lugs 32 preferably comprises a shank 32' next to the body 31, and an outer preferably substantially disk-shaped part 32'' with the shank 32' slightly narrower where it joins the part 32'', and 85 the part 32'' being somewhat dished to present a concave side inward against the outer side of the part 7' when it is clenched down thereon. The shank 32' is designed to have its length about equal to the aggregate thickness of the parts 6' and 7' through which it extends, and the narrower junction with the part 32'' serves to cause the lug 32 to bend abruptly at said junction when the clasping operation is to be completed; while by having the concave side against the clamped surface, the periphery of the part 32' is caused to embed slightly in the clamped material all around and thus afford a better clamping effect, as well as present a neater appearance, and be less liable to act as an obstruction on the exterior of the end of the finished box. 90 95 100

The clasp body 30 serving with its lugs 32 to clasp the end parts of the box firmly together, also serves for supporting the means that fastens down the top-forming parts 23 of the box. As here shown, this latter fastening means comprises a plate 33 hinged to the upper end of the clasp body 105 30 and having a middle slot 34' extending from its free end toward the hinge. The plate 33 is thus adapted to swing down over the top-forming parts 23 after they are folded down together across the top of the box; the upstanding handle-forming parts being received in the slot 34'. Near the free end of this plate 33 at one side of the slot 34', a flat U-shaped element 35 is pivoted to swing transversely through the adjacent slots 10 of the handle-forming parts when the plate 33 has thus been swung down; and the part of the plate 33 at the opposite side of the slot 34' preferably has a small tongue 36 pressed up out of its material under 110 115 120 125 130

which the free end of the element 35 may engage, as shown at the right in Fig. 5. The plate 34 and the upper part of the clasp body 30 to which it is hinged are preferably made amply wide to afford a sufficiently strong hinge joint. It will be understood that these parts 30, 34 and 35 may be conveniently made out of any suitable sheet metal.

10 It will likewise be understood that either the clasp part may be used without the hinged fastening plate for the top; or, such a fastening means for the top may be provided without the specific clasp for the end parts; 15 in either case any other suitable top-fastening or end-fastening means being used, such for instance, as the other examples given herein.

The sectional view in Fig. 7 shows smaller 20 containers 37 inclosed in the box with a horizontal partition 38 between them; and in Fig. 2, the box is shown as having a longitudinal vertical partition 38' along its middle. It will be understood that such smaller 25 containers or any other articles may be packed in the box, and such partitions, as shown, or others, may be introduced, as permitted by the size or grouping of the contained articles. Where partitions are used, 30 they reinforce the sides or ends of the box with which they come in contact; and the upright partition in some measure reinforces the top-forming parts 23. Another valuable result of the construction including the end 35 thicknesses 6 or 6' inside the thicknesses 7 or 7' is the support afforded for the ends of the top-forming parts 23, since these may rest directly on the upper edges 39 of these inner end thicknesses 6 or 6' when closed, as is 40 clearly shown in Fig. 7, and as is also seen in Fig. 2. It will be noted that these upper edges 39 lie somewhat below the folds 24 of the parts 4, so that the thickness of the top-forming parts 23 is received between these 45 upper edges 39 and the folded-over parts 4; and it is for the same purpose that the folds 20 are placed slightly farther from the ends of the sheet 1 than are the folds 24, as seen in Fig. 3 and as hereinbefore described.

50 The openings 9 in the handle-forming parts are preferably made with rounded ends and narrower in their middles, as shown, and when these register upon the parts being folded together, a very convenient handle is formed; it being of ample thickness to afford the required strength and to give the proper surface for a comfortable hand-hold due to the aggregation of the two thicknesses of material thus brought together. While the box is thus provided with double thickness in the handle-part, and in the ends and near the ends of the top where the parts are secured together and where the greatest strength is required, there 65 are no superfluous thicknesses of material

not needed for these purposes; and at no place in the structure is there any necessity for any tightly compressed folded part such as is necessitated by a construction involving superfluous material that must be folded under other parts. At the same time, there is no joint or fastening at any corner of the box where it is especially exposed to injury or disruption in the handling of the container. The bottom edges of the outer end 70 parts 7 or 7' are exposed, but these are immediately adjacent to the closed fold of the inner end part 6 or 6' and the fastening of the end parts is not confined to this region, but is distributed throughout the upright 75 middle of the box end where the exposure to damage is at a minimum. Likewise, with the parts or flaps 4 on the top. Their fastening is not dependent upon any outwardly exposed edges, but is provided at the middle 80 under the protection of the double thickness of the upstanding handle-forming parts.

It will be seen, therefore, that while my improved box or container is of very simple construction, a number of disadvantages of 85 such simply constructed containers are eliminated. While I have shown and described certain examples of my invention in considerable detail, it will be understood that I am not limited to such specific showing and description, but what I claim as new and desire to secure by Letters Patent is:

1. In a folding box, a bottom, sides, top-forming parts hinged to said sides to meet along the middle of the box, upward extensions on the respective parts where they meet, said upward extensions having openings, ends, parts hinged to said ends and adapted to fold down on said top-forming parts at opposite sides of said upward extensions, and means on some of said parts that are hinged to said ends, to engage in said openings in said upward extensions for holding down said top-forming parts and said parts hinged to said ends. 100

2. In a folding box, a bottom, sides, top-forming parts hinged to said sides to meet along the middle of the box, upward extensions on the respective parts where they meet, having registering openings near respective ends of the box, ends, parts hinged to said ends and adapted to fold down on said top-forming parts at opposite sides of said upward extensions, and means on some of said parts that are hinged to said ends, 115 to project into said openings in said upward extensions, for holding down said top-forming parts and said parts hinged to said ends. 120

3. In a folding box, a bottom, sides, top-forming parts hinged to said sides to meet along the middle of the box, upward extensions on the respective parts where they meet, having registering openings near respective ends of the box, ends, parts hinged to said ends and adapted to fold down on 130

5 said top-forming parts at opposite sides of said upward extensions, and means movably mounted on some of said parts that are hinged to said ends, to be projected into said openings in said upward extensions, for holding down said top-forming parts and said parts hinged to said ends.

4. In a folding box, a bottom, sides, top-forming parts hinged to said sides to meet 10 along the middle of the box, upward extensions on the respective parts where they meet, having registering openings near respective ends of the box, ends, parts hinged to said ends and adapted to fold down on 15 said top-forming parts at opposite sides of said upward extensions, and means pivotally mounted on some of said parts that are hinged to said ends, to be swung into said openings in said upward extensions, for 20 holding down said top-forming parts.

5. In a folding box, a bottom, sides hinged to opposite edges of said bottom, outer end parts hinged to opposite ends of the respective sides, inner end parts hinged to opposite 25 ends of said bottom, said inner end parts folding upwardly, and said outer end parts folding transversely inward and meeting substantially along upright median portions of said inner end parts, means to secure said 30 inner and outer end parts together when thus folded, top-forming parts hinged to the tops of said sides to meet along the middle of the box, upward extensions on the respective parts where they meet, parts hinged to 35 the tops of said outer end parts and adapted to fold down on said top-forming parts at opposite sides of said upward extensions, and means on some of said parts thus folded down, to engage with said upward extensions for holding down said top-forming 40 parts.

6. In a folding box, a bottom, sides hinged to opposite edges of said bottom, outer end parts hinged to opposite ends of the respective 45 sides, inner end parts hinged to opposite ends of said bottom, said inner end parts folding upwardly, and said outer end parts folding transversely inward and meeting substantially along upright median portions 50 of said inner end parts, means to secure said inner and outer end parts together when thus folded, top-forming parts hinged to the tops of said sides to meet along the middle of the box, upward extensions on the respective 55 parts where they meet, having registering openings near respective ends of the box, parts hinged to the tops of said outer end parts and adapted to fold down on said top-forming parts at opposite sides of said upward extensions, and means on some of said parts thus folded down, to project into said openings in said upward extensions, for holding down said top-forming parts.

7. In a folding box, a bottom, sides hinged 60 to opposite edges of said bottom, outer end

parts hinged to opposite ends of the respective sides, inner end parts hinged to opposite ends of said bottom, said inner end parts folding upwardly, and said outer end parts folding transversely inward and meeting 70 substantially along upright median portions of said inner end parts, means to secure said inner and outer end parts together when thus folded, top-forming parts hinged to the tops of said sides to meet along the middle of the 75 box, upward extensions on the respective parts where they meet, having registering openings near respective ends of the box, parts hinged to the tops of said outer end parts and adapted to fold down on said 80 top-forming parts at opposite sides of said upward extensions, and means movably mounted on some of said parts thus folded down, to be projected into said openings in said upward extensions, for holding down 85 said top-forming parts.

8. In a folding box, a bottom, sides hinged to opposite edges of said bottom, outer end parts hinged to opposite ends of the respective sides, inner end parts hinged to opposite 90 ends of said bottom, said inner end parts folding upwardly, and said outer end parts folding transversely inward and meeting substantially along upright median portions of said inner end parts, means to secure said 95 inner and outer end parts together when thus folded, top-forming parts hinged to the tops of said sides to meet along the middle of the box, upward extensions on the respective parts where they meet, having registering openings near respective ends of the box, parts hinged to the tops of said outer end parts and adapted to fold down on said top-forming parts at opposite sides of said 100 upward extensions, and means pivotally mounted on some of said parts thus folded down, to be swung into said openings in said upward extensions, for holding down said top-forming parts.

9. In a folding box, a single sheet of material of generally rectangular shape with slits extending in from its ends and slits extending in from its sides, substantially equidistant from and on opposite sides, respectively, of longitudinal and transverse median 110 lines, leaving middle parts and flanking parts at the ends and sides of the sheet, with the adjacent side and end flanking parts integral, the side flanking parts projecting laterally less than the width of the respective middle parts at the sides, and all of said parts being folded up on lines extending transversely or longitudinally, as the case may be, from their adjacent slits across the 115 respective parts, with the flanking parts outside the middle parts, and means to fasten the respective adjacent middle and flanking parts together when the folding is completed.

10. In a folding box, a single sheet of ma- 130

terial of generally rectangular shape, with slits extending in from its ends and slits extending in from its sides, substantially equidistant from and on opposite sides, respectively, of longitudinal and transverse median lines, leaving middle parts and flanking parts at the ends and sides of the sheet, with the adjacent side and end flanking parts integral, the side flanking parts projecting laterally less than the width of the respective middle parts at the sides, and all of said parts being folded up on lines extending transversely or longitudinally, as the case may be, from their adjacent slits across the respective parts, with the flanking parts outside the

middle parts, said end middle parts also having transverse downward folds whereby upward extensions are formed, to meet when the other folds are completed, and said end flanking parts being cut away on their outer edges, whereby they flank said upward extensions when the other folds are completed, and means to fasten the respective adjacent middle and flanking parts together when the folding is completed. 20
